(57) **CLAIM**

The ornamental design for a portable battery charger, as shown and described.

DESCRIPTION

FIG. 1 is a top perspective view of a portable battery charger of the claimed invention.

FIG. 2 is a bottom perspective view of the portable battery charger of FIG. 1.

FIG. 3 is a front side elevation view of the portable battery charger of FIG. 1.

FIG. 4 is a back side elevation view of the portable battery charger of FIG. 1.

FIG. 5 is a left side elevation view of the portable battery charger of FIG. 1.

FIG. 6 is a right side elevation view of the portable battery charger of FIG. 1.

FIG. 7 is a top plan view of the portable battery charger of FIG. 1; and,

FIG. 8 is a bottom plan view of the portable battery charger of FIG. 1.

The broken lines shown in the drawings illustrate portions of the portable battery charger which form no part of the claimed design.
